UNITED STATES PATENT OFFICE.

CHARLES ARMSTRONG MATHENY, OF HIGH SPRINGS, FLORIDA.

MACHINE FOR TURNING CROSS-HEAD PINS.

SPECIFICATION forming part of Letters Patent No. 745,214, dated November 24, 1903.

Application filed February 18, 1903. Serial No. 143,981. (No model.)

To all whom it may concern:

Be it known that I, CHARLES ARMSTRONG MATHENY, of High Springs, in the county of Alachua and State of Florida, have invented 5 a new and useful Improvement in Machines for Turning Cross-Head Pins, of which the following is a specification.

My invention is in the nature of a novel construction of machine for turning the pins of cross-heads for steam and other engines. The cross-head pin which receives the pitman is ordinarily formed integral with the yoke portion of the cross-head and is connected to it between its jaws or branches at both its ends. 15 This makes it difficult and inconvenient to turn said pins to a true cylinder. My invention is designed to accomplish this work in a convenient, accurate, and practical way; and to that end it consists in the novel construction and arrangement of machine for this purpose which I will now proceed to describe with reference to the drawings, in which— 20 Figure 1 is a front elevation; Fig. 2, a side elevation; Fig. 3, a plan view; Fig. 4, a vertical section on line 4-4 of Fig. 1; Fig. 5, a detail; Fig. 6, a front view of a modification, and Fig. 7 a detail relating thereto.

In general construction my invention comprises an annular or ring-shaped turning-head, which is made in sections and put together around the cross-head pin and is provided with cutting-bits and means for rotating said head and bits and for feeding the same and also the cross-head as the work progresses. 35

In the drawings, G G represent the two parallel branches of the cross-head, and D is the cross-head pin, which occupies a position between the two branches or jaws and is formed 40 in one piece with the same. It is this pin D and the inner sides of the cross-head jaws which are to be turned and planed true by my machine. The cross-head is blocked up to a proper position by strips N N, Fig. 1, on top 45 of two bed-plates L L and is firmly held to the same by headed bolts a a, with nuts a' a', clamp-plates a² a², and upright detachable bars a³ a³. The bolts have their heads retained in undercut grooves of the bed-plates. 50 The upright bars a³ are placed between the outer ends of the clamp-plates a² and the tops

of the bed-plates L, and when the nuts a' are screwed down the clamp-plates are made to pinch and hold the cross-head firmly on the bed-plates L L. These two bed-plates are 55 thus firmly held together by the cross-head and constitute the carriage for the cross-head. The bed-plates L have undercut transverse grooves on their under sides (see Fig. 4) where they rest upon the parallel ways U of 60 the main frame, and these ways have flanged edges fitting said grooves. These bed-plates forming the carriage are fed along the length of the ways by a horizontal screw-stem J', Fig. 1, tapped through a screw-threaded lug 65 J² on the lower side of one of the bed-plates L, and this screw swivels in one of the end frames V and is turned by a belt-pulley J, as hereinafter described. When the screw is turned, it causes the carriage and the cross- 70 head to be moved in a direction parallel to the axis of the cross-head pin, so that the latter may be fed into the plane of the cutters of the turning-head to successively bring all parts of the pin into range of the cutting action. 75

A is the rotating turning-head made as a ring in four sections with lap-joints and bolted together around the cross-head pin. This turning-head carries the cutting-tools and is 80 formed on its outer periphery with a circular series of gear-teeth, which are in mesh with and receive rotary motion from a superposed driving gear-wheel A', rigidly fixed to a main drive-shaft W above, turning in bearings in the top of the two upright end frames V V.

F is the ring-shaped steady-rest or stationary guide for the turning-head A, the turning-head being grooved circularly on the outer 90 periphery to receive this steady-rest and turning freely in the latter. This steady-rest is made in two semicircular sections bolted together around the turning-head and is rigidly held by a horizontal arm F' above and F² 95 below the position of the cross-head. These arms are formed with two semicircular sections F³ F³, bolted to the inner side of one of the upright end frames V and concentric with the steady-rest F. 100

The cutters for turning the pin D of the cross-head are arranged in radial dovetail

grooves *g*, Figs. 1 and 4, of the turning-head and are adjustable toward the center of the cross-head pin. *C* represents one of these cutters. On the opposite side of the turning-head there is another radial dovetail groove which receives a cutter-head *B*, which on its outer face has another radial dovetail groove, (see Fig. 4,) that receives the shank of a cutter *S*, that has a cutting action at right angles to that of the cutter *C* and is not designed to act upon the cross-head pin, but against the inner sides of the two branches or jaws of the cross-head. To hold this cutter-head tightly, a taper key with a screw *T* (see Fig. 4) is adjustably fixed beside it. When not using this cutter-head to dress the side walls of the cross-head, the cutter-head *B* is removed and a cutter *C* is placed in its groove to act upon and turn the cross-head pin *D*.

To feed the cutter-head *B* down automatically when dressing the inner side walls or jaws of the cross-head, the outer end *e* of the cutter-head is made inclined, its forward edge being nearer the center than its rear edge, and in the plane of this cutter-head and tapped in the upper arm *F'* there is a feed-screw *R*. This screw has a longitudinal slot *r*, and around the screw, above the arm *F'*, there is a collar *I*, having no internal screw-threads, but having a lug *i*, that enters the slot *r* of the screw. This collar also has a series of upwardly-projecting teeth *v*. The screw *R* is set down to contact with the cutter-head *B*, and when the cutter-head revolves with the annular turning-head the outer inclined face *e* of the cutter-head strikes the inner end of the screw *R*, and the cutter-head is forced inwardly toward the center to cause the cutter *S* to cut a new track in a smaller circle on the side wall or jaw of the cross-head. This screw *R* is automatically fed down at each revolution to continually send the cutter-head closer to the center, and for this purpose the main driving gear-wheel *A'* has a radial slot carrying an adjustable tappet-lug *l*, that lies in the plane of the teeth of the collar *I*, so that at each revolution of the gear-wheel *A'* the collar *I* is turned slightly and the lug *i* of the collar, resting in the slot of the screw, gives a corresponding turn to the screw at each revolution, that causes the screw to follow up the cutter-head *B* and intermittently force it and its cutter *S* toward the center. When the cutter-head *B* is adjusted into the dovetail groove on the other side of the turning-head *A* to dress the other inner face of the cross-head, said cutter-head is intermittently fed down in an automatic manner by a second feed-screw *R'* and collar *I'* on the other side, (see Fig. 1,) which are carried by a rigid horizontal arm *M*, projecting inwardly from the other end frame *V*.

To drive the gear-wheel *A'*, a smaller gear-wheel *A''* is arranged behind it in mesh with it, (see Figs. 3 and 4,) and this wheel is fixed rigidly to a shaft *A''*, which derives its mo-

tion from a belt through the cone-pulley *P* or from a crank *Q* from any suitable source of power.

In order to run the carriage *L* back or forward to turn the full length of the cross-head pin, the pulley *J*, which turns the feed-screw of the carriage, is connected (see Fig. 2) by a belt *K'* to a pulley *K*' on a swinging plate *K*. This plate is pivoted about the axis of pulley *K*' and has a curved slot and set-screw *O*. This plate also carries three gear-wheels 1, 2, and 3, of which 1 is rigidly fixed to the pulley *K*', and 2 and 3 turn loosely upon centers on the plate *K*. On the end of main drive-shaft *W* there is a rigidly-attached gear-wheel *W'*, and this gear-wheel is adapted to mesh directly either with gear-wheel 2 or 3. Gear-wheel 2 is always in mesh with gear 1, as the plate *K* is pivoted about the center of 1. Now when the gear-wheel *W'* is in mesh with 2 the power is transmitted from *W'* to 2 and thence to 1, gear 3 then running idle. If, however, plate *K* is swung over, so that 3 is in mesh with *W'*, and 2 is out of mesh with *W'*, then the power is transmitted from *W'* to 3 and thence through 2 to 1, and as this interposes another gear-wheel in the train the effect is to reverse the direction of revolution of the belt and the feed of the screw.

To center and adjust the cross-head in the machine, I employ a disk *Y* with a pointed center *y*. (See Fig. 5.) This disk is made to fit the concentric ring *F'' F''* of the steady-rest. Now, assuming that the cross-head is out of the machine and is about to be inserted, the first thing is to mark on the outer face of the cross-head jaws the center of the pin, as at *x*. Then the centering-disk *Y* is placed in the ring *F'' F''*, as in dotted lines in Fig. 1. Then the cross-head is lined up with its marked center *x* in line with the center point *y* of the disk *Y*. The cross-head is blocked up to this position by the strips *N* and is then secured by the clamps. The four sections of the turning-ring and steady-rest are then bolted together around the cross-head pin, and the cross-head pin will then be centered in the turning-head and the cutting action may begin.

In Fig. 6 I show a modification of my invention, in which it is constructed as an attachment to a lathe. The cross-head to be turned is adjusted against an angle-plate *Z''*, bolted to the lathe-carriage *Z'*. The steady-rest *F* with its arms *F' F''* and semicircular sections *F'' F''* are bolted to the tail-stock *T''* of the lathe. A driving-shaft *W''* with a gear-wheel *A''* is adjusted to the lathe-centers *c c*, and a yoke-clamp *O''* (see Fig. 7) fits over the lathe-center *c'* of the tail-stock and connects with and braces the steady-rest arm *F'*. The cross-head *G* is fed through the turning-head in a direction parallel to the axis of the shaft *W''* by the regular back-and-forth feed of the lathe; but the steady-rest, turning-head, and automatic screw-feed and other features are

the same as those already described with reference to Figs. 1, 2, 3, and 4.

I am aware that a ring-shaped sectional turning-head with inwardly-projecting cutters and gear-teeth on its outer periphery is not broadly new for turning wrist-pins, &c., and I make no claim to them.

Having thus described my invention, what I claim as new, and desire to secure by Letters Patent, is—

1. In a machine of the kind described, the combination with the ring-shaped turning-head; of a radially-adjustable cutter-head having an outer inclined end, a feed-screw arranged to act upon said inclined end of the cutter-head with a cam action as the cutter-head revolves, a stationary support for the feed-screw, and means for imparting an advancing motion to said feed-screw substantially as shown and described.

2. In a machine of the kind described, the combination with the ring-shaped turning-head; of a radially-adjustable cutter-head carried by the turning-head and having an inclined outer end, a longitudinally-slotted feed-screw arranged to act upon the incline of the cutter-head as it revolves, a stationary support for said feed-screw, an unthreaded collar with tappet-teeth arranged on the feed-screw and having a lug entering the slot of the screw, a superposed drive-shaft carrying a tappet-lug adapted to strike the tappet-teeth of the collar and feed down the screw with an intermittent but automatic action substantially as described.

3. In a machine of the kind described, a sectional ring-shaped turning-head with cutters and peripheral driving-teeth, a ring-shaped steady-rest encircling and guiding the turning-head and made in sections as described, an upper and lower horizontal arm connecting the steady-rest to the main frame, a carriage for the work located between the said

upper and lower arms, and means for feeding said carriage substantially as described.

45

4. In a machine of the kind described, a sectional ring-shaped turning-head with cutters and peripheral driving-teeth, a ring-shaped steady-rest encircling and guiding the turning-head and made in sections as described, an upper and lower horizontal arm connecting the steady-rest to the main frame, a carriage for the work located between the said upper and lower arms and consisting of two undercut bed-plates with headed bolts, clamp-plates, and upright bars, horizontal ways for the bed-plate, and a feed-screw for the carriage substantially as shown and described.

50

5. In a machine of the kind described, a ring-shaped turning-head, a ring-shaped steady-rest made in sections and embracing the turning-head, upper and lower horizontal arms supporting the steady-rest, a circular end frame for these arms arranged concentric to the steady-rest and turning-head, and a detachable center fitting in the said circular end frame to facilitate the fitting of the work to the axial center for turning substantially as described.

60

6. In a machine of the kind described, the combination of a ring-shaped turning-head bearing cutters and peripheral teeth, a superposed driving-shaft with gear-wheel meshing with the turning-head and another gear at the end of the shaft, a carriage for holding the work in the turning-head having a feed-screw with a pulley at its end, a driving-belt, and a swinging and adjustable plate K bearing gears 1, 2, 3 adapted to receive power from the end gear of the driving-shaft for moving the carriage back and forth as may be desired substantially as set forth.
